(57) **CLAIM**
The ornamental design for a lantern, as shown and described.

DESCRIPTION

FIG. 1 is a perspective view of a lantern according to the present invention, with the top portion extended up.

FIG. 2 is a front elevational view of the lantern, with the top portion extended up.

FIG. 3 is a rear elevational view of the lantern, with the top portion extended up.

FIG. 4 is a right side elevational view of the lantern, with the top portion extended up.

FIG. 5 is a left side elevational view of the lantern, with the top portion extended up.

FIG. 6 is a top plan view of the lantern, with the top portion extended up.

FIG. 7 is a bottom plan view of the lantern, with the top portion extended up.

FIG. 8 is a perspective view of a lantern according to the present invention, with the top portion in the lowered position.

FIG. 9 is a front elevational view of the lantern, with the top portion in the lowered position.

FIG. 10 is a rear elevational view of the lantern, with the top portion in the lowered position.

FIG. 11 is a right side elevational view of the lantern, with the top portion in the lowered position.

FIG. 12 is a left side elevational view of the lantern, with the top portion in the lowered position.

FIG. 13 is a top plan view of the lantern, with the top portion in the lowered position; and,

FIG. 14 is a bottom plan view of the Lantern, with the top portion in the lowered position.

The broken line showing is for environmental purposes only and forms no part of the claimed design.
